(57) **CLAIM**

The ornamental design for a endpoint for videoconference, as shown and described.

DESCRIPTION

FIG. 1 is a front view of a endpoint for videoconference, showing my design;

FIG. 2 is a rear view thereof;

FIG. 3 is a right side view thereof;

FIG. 4 is a left side view thereof;

FIG. 5 is a top view thereof;

FIG. 6 is bottom view thereof;

FIG. 7 is top and left front perspective view thereof; and,

FIG. 8 is a top and right rear perspective view of the endpoint for videoconference.

UNITED STATES PATENT AND TRADEMARK OFFICE
CERTIFICATE OF CORRECTION

PATENT NO. : Des. 579,888 S
APPLICATION NO. : 29/297410
DATED : November 9, 2007
INVENTOR(S) : Finn Helge Lunde et al.

Page 1 of 1

It is certified that error appears in the above-identified patent and that said Letters Patent is hereby corrected as shown below:

On the title page, item (73), add:

-- (73) Assignee: Tandberg Telecom AS
Lysaker, NORWAY --

Signed and Sealed this

Ninth Day of December, 2008

JON W. DUDAS
Director of the United States Patent and Trademark Office

UNITED STATES PATENT AND TRADEMARK OFFICE
CERTIFICATE OF CORRECTION

PATENT NO. : Des. 579,888 S
APPLICATION NO. : 29/297410
DATED : November 4, 2008
INVENTOR(S) : Finn Helge Lunde et al.

Page 1 of 1

It is certified that error appears in the above-identified patent and that said Letters Patent is hereby corrected as shown below:

On the title page, item (73), add:

-- (73) Assignee: Tandberg Telecom AS
Lysaker, NORWAY --

This certificate supersedes the Certificate of Correction issued December 9, 2008.

Signed and Sealed this
Thirtieth Day of December, 2008
